INVENTOR

BY *Victor J. Evans*

WITNESS:

UNITED STATES PATENT OFFICE.

ISAAC LEE HORNE, OF WEST GRAHAM, VIRGINIA, ASSIGNOR OF ONE-HALF TO PHILIP BURKETT, OF WEST GRAHAM, VIRGINIA.

BULLETIN CABINET.

Application filed August 29, 1924. Serial No. 734,972.

To all whom it may concern:

Be it known that I, ISAAC LEE HORNE, a citizen of the United States, residing at West Graham, in the county of Tazewell 5 and State of Virginia, have invented new and useful Improvements in Bulletin Cabinets, of which the following is a specification.

The object of my said invention is the provision of an extremely simple, strong, and easily operated and durable bulletin cabinet in the nature of an indicator, designed to be used to advantage in railway stations for announcing trains and also 15 adapted to be employed for other indicating purposes.

My invention consists in my cabinet or indicator as hereinafter described and definitely claimed.

20 In the accompanying drawings, forming part of this specification:—

Figure 1 is a front elevation of the device constituting the preferred embodiment of my invention.

25 Figure 2 is a view of the same with the top wall removed and with the casing body in section.

Figure 3 is a vertical cross-section taken in the plane indicated by the line 3—3 of 30 Figure 2.

Similar numerals of reference designate corresponding parts in all of the views of the drawings.

Among other elements my novel device 35 comprises a casing body 1 on which is fixed in appropriate manner a top wall 2. The front wall of the casing body 1 is designated by 3, and it will be noted that the said front wall is provided with a plurality of openings designated by 4, 5, 6 and 7. These 40 openings are preferably, though not necessarily, provided with glass or other appropriate transparent material, the glass being resorted to in order to exclude dust and dirt 45 from the interior of the casing.

Extending longitudinally in the casing body 1 and carried by the end walls thereof as appears in Figure 2 is a shaft 8 which may be and preferably is made fast to the 50 casing body.

Loosely mounted on the said shaft 8 are four (more or less) wheels 9, 10, 11 and 55 12. Each of the said wheels is provided at one side with a ratchet disk 13, and in conjunction with each ratchet is employed

a pawl 14 which is resilient in character and is fixed to and extends upwardly from the bottom wall of the casing body 1 so as to engage its respective disk in a vertical plane back of the vertical plane of the shaft 8 as 60 appears in Figure 3. I also employ in conjunction with each of the said wheels and its ratchet disk 13 a vertically swinging lever 15 fulcrumed on and connected to the shaft 8 and provided with a spring-pressed dog 65 16 arranged to engage its respective ratchet as shown in Figure 2, and in conjunction with each lever 15, I employ retractile spring 16^x and a pendent rod 17. Each spring 16^x is connected to its respective 70 lever 15 and is interposed between said lever and the top wall 2 to which it is connected at its upper end as shown. Each rod 17 is connected to its respective lever 15 and is carried downwardly and through an opening 18 75 in the bottom wall of the body 1 and is provided with an appropriate handle grasp 19. It will be noted that the construction described is positive in operation, and that the parts appurtenant to each of the four 80 wheels normally rest in the positions shown in Figure 3. Therefore, when it is desired to turn any one of the said wheels about its axis it is simply necessary for an operator to pull downwardly on the handle 19 in 85 connection with the particular wheel to the extent desired for the movement of the wheel through a greater or less portion of a circle; and it will also be noted when the handle 19 is released the spring 16^x will 90 promptly return the lever 15 to the position shown in Figure 3, while the pawl 14 will prevent retrograde movement of the wheel and will also exert pressure against the periphery of the ratchet disk 13 and thereby 95 prevent casual movement of the wheel in the direction in which it is moved by downward movement of the lever 15.

As shown in Figure 1 the openings in the casing body 1 are provided with legends appropriate to a railway station and having to do with the expected arrival of trains, the opening 4 being intended to display the number of a train, the opening 5 the hour of its arrival, the opening 6 the minute of its 105 arrival and the opening 7 the information as to whether or not the train is late.

Manifestly those of the wheels in the casing body that bears numbers have the numbers arranged in regular sequence so that 110

by repeatedly actuating the lever 15 and turning any one of the wheels step by step, the operator is enabled to adjust the wheel until the desired number or legend is displayed through the opening opposite and in the same vertical plane as the periphery of the particular wheel.

It will be apparent from the foregoing that my novel bulletin cabinet is not only 10 highly useful, but is simple and durable in construction and is susceptible of being conveniently actuated for the display of the information that it is desired to impart.

The construction herein shown and 15 described constitutes the preferred embodiment of my invention and I have specifically described such construction in order to impart an exact understanding of the same. It is to be understood, however, that the 20 scope of my invention is defined by my appended claim within which changes or modifications may be made without departure from my invention.

Having described my invention, what I 25 claim and desire to secure by Letters-Patent, is:—

The combination in a bulletin cabinet, of a casing body having display openings in

one wall thereof indicating wheels supported in said casing body opposite the said display openings and adapted to bear on their peripheries and in spaced relation with respect to each other data items of various description, ratchet disks fixed to said wheels at the sides thereof, right angled shaped resilient pawls rising vertically from and fixed to the bottom of the casing body and having their upper ends bearing against the peripheries of the ratchet disks respectively at one side of the center of movement thereof, 40 vertically swinging levers arranged alongside said ratchet disks and movable about said center of movement, dogs carried by said levers and arranged to engage the ratchet disks at the opposite sides of the 45 center of movement to the said resilient pawls, retractile springs interposed between and connected to the levers and the casing top, and rods connected to the levers at the connection of the springs therewith and extending through openings in the bottom of the casing body and hand grasp portions on the rods and arranged below said bottom.

In testimony whereof I affix my signature.

ISAAC LEE HORNE.
